United States Patent Office

Des. 193,341
Patented Aug. 7, 1962

193,341

CENTRIFUGE

Frank I. Fuller, Menlo Park, Calif., assignor to Beckman Instruments, Inc., a corporation of California

Filed Aug. 30, 1960, Ser. No. 61,955

Term of patent 14 years

(Cl. D16—2)

The FIGURE is a front perspective view taken from the right side of the centrifuge embodying my design.

The side and rear views of the centrifuge which are not shown are substantially like the side shown.

The transverse lines on the body and base of the centrifuge represent contrasting colored areas.

The dominant features of my design reside in the full line portions of the drawing.

I claim:

The ornamental design for a centrifuge, substantially as shown and described.
